UNITED STATES PATENT OFFICE.

JAMES DARIUS CULP, OF SAN FELIPE, CALIFORNIA.

ELECTRICAL TORCH FOR LIGHTING GAS.

SPECIFICATION forming part of Letters Patent No. 336,898, dated March 2, 1886.

Application filed May 6, 1885. Serial No. 164,558. (No model.)

To all whom it may concern:

Be it known that I, JAMES DARIUS CULP, a citizen of the United States, residing at San Felipe, in the county of Santa Clara and State 5 of California, have invented certain new and useful Improvements in Electric Torches for Lighting Gas, of which the following specification is a full, clear, and exact description.

This invention relates more particularly to 10 a hand implement for lighting gas by means of an electric spark, of which a portable electric generator forms part.

Heretofore various implements of this kind have been devised, but they have not come 15 into general use, probably because they require considerable trouble to operate or (if a galvanic battery is used) to keep in order, and cannot be relied upon under the different conditions under which they would ordinarily be 20 used.

The object of the present invention is to overcome these difficulties, or enough of them to render the implement commercially successful.

25 To this end the invention consists in an electric torch in which the electrodes or terminals, between which the electricity is discharged, are protected, nearly or quite to the discharging-point, from contact with the gas to be lighted.

30 I find that where a considerable surface is exposed (as it heretofore has been) the illuminating-gas will conduct or carry off the electricity, so as to produce, especially under unfavorable conditions, a silent discharge, or at 35 least one not having heat enough to produce ignition.

The invention also consists in certain new 40 constructions of parts in the generator. Heretofore it has been customary to employ either a galvanic battery, which is not desirable on account of the consumption of material, or a friction or induction apparatus having a revolving inductor or armature, which is not desirable on account of the necessity of rotating 45 or turning the said part whenever the apparatus is to be used. An instrument, however, has been devised, in which an electrophorus was employed, the spark being produced by simply moving the induced plate by 50 means of a lever attached thereto. In this instrument the induced plate was not in permanent electrical connection with the discharg-

ing or terminal electrode, but the connection was made when the induced plate had been separated from the inducing-plate or electrified non-conductor by contact of the former with a projecting arm, from which a conductor ran to the discharging-electrode. Moreover, the gas or gas-fixture was relied upon to complete the circuit to the ground, and the construction or shape and dimensions of the different parts of the electrophorus was such that it had only a small capacity. The inducing-plate was in the form of a cylinder surrounding a metal rod, which constituted the 55 sole or ground conductor, and the induced or discharging plate was curved and fitted over one side of the electrified cylinder. In the present invention the induced or discharging plate is in permanent electrical connection 60 with the discharging electrode or terminal, and it is unnecessary to employ a projecting arm to be in the way, or an additional contact to increase the resistance in the charging-circuit, and diminish the intensity of the spark, 65 in order to insure a complete circuit; also, the opposing electrode or terminal opposite that connected with the induced plate is in electrical connection with the ground through the instrument, and no care is required in order to 70 insure a ground connection. These constructions are claimed as new only in connection with an electrophorus in which the parts are simply brought in contact without being rubbed together; also, the sole, the electrified 75 non-conductor, and the induced plate are made broad, and preferably flat, (not curved, although this is less important,) and they are fastened to or carried by a parallel stiff rod 80 terminating in a handle. This form of electrophorus is found to possess large capacity, and to retain its electrification for a long time. Pins project from the sole through the electrified or inducing non-conductor to make 85 contact with the induced plate. Two pins are 90 considered preferable to one.

The present invention also consists in an electric torch in which the spanner or fork for turning on the gas is placed in the end of the torch, the electrodes or terminals being 95 placed just below it, and also in the combination, with the electrodes, of a sort of hood, which extends over the electrode on one side and collects the gas. These arrangements are

much neater and handier than those heretofore employed in which the electrodes were placed with a collecting-bell at the end of a curved arm, so that the igniting device had to be 5 placed over the gas-burner, whereas with the improved torch it is only necessary to insert it anywhere in close proximity to the burner. They are also more efficient and useful than those in which the discharging points are 10 placed at the upper end of the torch without any means whatever of collecting gas, or in which a spanner or fork is not employed.

The invention further comprises certain particular constructions, combinations, and 15 arrangements of parts, as hereinafter set forth.

The following is a description of what is considered the best mode of applying the principle of the invention, reference being had to the accompanying drawings, which form a 20 part of this specification.

Figure 1 is a front view of a gas-lighting torch constructed in accordance with the invention; Fig. 2, a back view; Fig. 3, an edge view; and Fig. 4 a cross-section on line *x* *x*, 25 Fig. 2.

The inducing-plate A, of non-conducting material, (preferably hard rubber,) is placed over the metal sole C, which is in the form of a flat plate as well as the inducing-plate A, 30 and both plates are fastened by screws, rivets, or pins *a*, of metal, to the metallic bar Q. As shown, the screws have the nick in the point, so as to leave the head perfectly plain. This bar carries the plates, and also stiffens or braces 35 them. It terminates in a handle, D, made of or coated with metal, so that when it is held in the hand there is an electrical connection from the pins *a* and sole C to the ground. The induced or discharging plate B, of metal, is 40 carried by the lever E, of non-conducting material, (wood will answer,) which lever is fulcrumed on the pin F, fitting in ears on the bar Q. A spiral compression-spring, *w*, acting upon the tail of lever E, tends to press the 45 induced plate B against the inducing-plate C. The inducing-plate B is in permanent electrical connection with the discharging electrode or terminal *k* by means of the wire *o*, the upper end of which, as shown, constitutes 50 the said electrode. The wire is embedded in the rod G, of insulating material, except at the lower end, and also at the discharging-point opposite the electrode *m*, in order to permit the spark to pass, and even 55 here it is exposed only on one side. (See Fig. 4.) The opposing electrode *m* is also protected from contact with the illuminating-gas by the block *h*, of insulating material, except at the outer end. The wire *o* fits loosely in a 60 hole in the pin K, and is coiled between said pin and where it enters the insulating-rod, in order to increase its flexibility. The insulating-rod G is fastened to the frame of the torch in any suitable way. As shown, an 65 ear, *r*, on the sole C fits into a slit in the lower end of the rod, and is there fastened by a rivet. From the upper end of the sole pro-

ject the rods *i* *i'*, fastened to or in one piece with the sole. The upper ends of these rods are connected together by the spanner or fork P, for turning on the gas, and also by the hood J, at one side of the electrodes, for collecting the gas and retaining it in contact with the discharging-points.

As shown, the bars *i* *i'* form an electrical 75 connection between the sole C and the electrode *m*; but it is not essential that the electrical connection should be made in this way. The electrode *m* is in the form of a screw tapped through the bar *i'*, so that it can be 80 adjusted with reference to the electrode *k*.

For use the plate A is electrified by rubbing with a silk handkerchief or otherwise. To enable this to be done, the induced plate B can be removed by taking out the pin F. 85 When the plate B rests upon the non-conducting plate A, it is in electrical connection with the sole C through the pins or screws *a*, and is charged with electricity of opposite name to that with which the plate A is charged. 90 When the induced plate B is lifted away by pressing upon the tail of lever E, the charge, being freed from the attraction of the charge of plate A, passes by way of the wire *o*, electrodes *k* *m*, bars *i* *i'*, sole C, bar Q, handle D, 95 and body of the user to ground. In passing between the electrodes a spark is produced which will ignite the gas if the upper end of the torch is placed in proximity to the gas-burner after the gas has been turned on. The 100 open side of the hood J should be turned toward the burner, so as to collect in issuing gas. The gas can be turned on by the spanner or fork P, or by other means. The electric igniting devices do not interfere with the 105 ready use of the spanner, nor the latter with the ready operation of the former. After the spark has been produced in the manner described the lever E is released, and the spring *w* returns the plate B, when it receives a new 110 charge.

It is obvious that modifications may be made in details without departing from the spirit of the invention and parts of the invention be used separately.

I claim the new improvements herein described, all and several, to wit:

1. In an electric igniting apparatus, and in combination with an electric generator or source of electricity, the electrodes or terminals, between which the electricity is discharged, protected by an envelope to the discharging-points from contact with the gas to be lighted, to prevent dissipation of the charge by the gas, substantially as described.

2. The combination, with discharging electrodes or terminals of an electric igniting device, of an electrophorus having the induced plate carried by a lever, and a wire embedded in a rod of insulating material and forming a 120 constant or permanent electrical connection between said plate and one of said electrodes, substantially as described.

3. The combination, with the discharging

- electrodes or terminals of an igniting device, and an electrophorus having the induced plate carried by a lever and arranged parallel to the length of the torch, of an electrical connection 5 between one electrode or terminal and the sole or ground conductor of the electrophorus, and a second connection between the other electrode or terminal and the induced plate of the electrophorus, substantially as described.
- 10 4. The combination, with the elongated frame having a handle at one end and the electrodes or terminals at the other end of said frame, of the sole and inducing non-conductor, both in the form of plates attached to 15 said frame parallel to the length thereof, the induced conductor, also in the form of a plate placed directly outside said non-conductor, so that it may rest against it, the lever carrying said induced conductor, and the permanent 20 electrical connections between the sole and induced conductor and the respective electrodes or terminals, substantially as described.
- 25 5. The combination of the stiff rod provided with a handle, the sole, and the inducing-plate carried thereby, the metal pins or screw connecting said parts and forming a conductor for putting the induced plate in electrical connection with the sole, the lever fulcrumed on 30 said rod, and the induced plate carried by said lever, substantially as described.
- 35 6. The combination, in an electric torch or igniter, with the discharging electrodes or terminals and the frame or rods at the end of which said electrodes are placed, of the electrophorus at the opposite end of the implement, formed of a sole and inducing non-conductor, both in the form of plates, and an in- 40 duced plate carried by a lever, the induced plate being connected electrically with one electrode and the sole or ground conductor 45 with the other electrode, substantially as described.
7. The combination, with the electric generator of a gas-lighting torch, of the two bars, the spanner or fork connecting their upper ends, and the discharging electrodes placed just below the said spanner in the space between said bars, substantially as described.
8. The combination, in an electric torch or igniter, with the discharging electrodes or 50 terminals, of the hood inclosing one side of said electrodes or terminals, substantially as described.
9. The combination, with the electrophorus, of the discharging-electrodes connected therewith and protected by an envelope from contact with the gas to be ignited, except at the discharging points, substantially as described. 55
10. The herein-described electric torch or igniter, comprising an elongated frame, an electrophorus at the lower end thereof having an induced plate carried by a lever, a spanner or fork at the upper end, and the discharging electrodes or terminals, also at the upper end, and connected, one electrode with the induced 60 plate, and the other with the sole or ground conductor of the electrophorus, substantially as described.
